James F. Duhamel,
ATTORNEY

UNITED STATES PATENT OFFICE.

ISRAEL GITENSTEIN, OF NEW YORK, N. Y.

GARMENT.

1,323,748.

Specification of Letters Patent. Patented Dec. 2, 1919.

Application filed November 24, 1917. Serial No. 203,836.

To all whom it may concern:

Be it known that I, ISRAEL GITENSTEIN, a citizen of the United States, and resident of New York, in the county of New York and State of New York, have invented certain new and useful Improvements in Garments, of which the following is a specification.

This invention relates to garments and more especially to bifurcated or union garments and its object is to provide means at a convenient point to close the garment around the body of the wearer so that the front of the former will be without opening or seam and to strengthen and reinforce the garment around the neck of the same.

These and other details and objects of the invention will be more fully described in the following specification, set forth in the appended claim and illustrated in the accompanying drawings, wherein:

Figure 1 is a front view of the upper part of the garment.

Fig. 2 is a rear view of the same.

Fig. 3 is a detail view of the closing flap unfastened.

In addition to symmetrical appearance at the front of the garment the placket which has heretofore been used in this class of apparel, on account of the strain often put upon it, is apt to have its fastenings pulled out and the extremity of the opening pulled out so that the garment is split and soon destroyed.

This is especially so if the garment is close fitting and to strengthen the same its front part 5 is made without a seam and around the neck a strengthening yoke 6 is made and a reinforcing piece added for any desired depth to form a comfortable closure, especially in cold weather, and at a point where the old style placket affords little protection against the entrance of cold air, and in addition the scratching of threads and buttons on that part of the body may be very disagreeable.

The yoke 6 has extensions 7 at each side to cover the shoulders of the wearer and to

these extensions are added the flaps 8 to lap over the shoulders as will be seen in Fig. 2 and where is also shown a reinforcing strip 50 9 at the upper edge of the back of the garment and extending to the arm holes 10. The strip 9 conforms to the neck of the wearer and its ends coöperate with the flaps 8 to suspend the garment on his shoulders 55 and have fastening means of any desired nature.

The strip 9 is shown provided with buttons 11 while the flaps have button holes 12, but it is obvious that glove fasteners or 60 hooks and eyes may be also used and in removing or donning the garment and that either one or both of the flaps may be released and in case that one flap is opened, sufficient room will be found to allow the 65 entrance or exit of the head and shoulders of the wearer so that the garment may be then stripped off the body by way of the legs of the wearer.

The arm holes 10 may be edged with suitable binding 13 and a webbing 14 will provide for the girth of the wearer, while the lower part of the garment may be arranged for any preferred construction.

It is obvious that this arrangement of a 75 garment about the neck and shoulders of the same is not confined to a bifurcated garment only but any undergarment may be so provided without departing from the essential features above described or from the scope 80 of the appended claim.

What I claim as new is:

In a garment, the combination with a one-piece garment separated at its top, reinforcing strips at the top edge of the garment and 85 conforming with the same, extension straps from and integral with one of the strips, and fastening means for the straps on the other strip.

Signed at New York in the county of New 90 York and State of New York this 23 day of November A. D. 1917.

ISRAEL GITENSTEIN.
